UNITED STATES PATENT OFFICE

SAMUEL A. NEIDICH, OF EDGEWATER PARK, NEW JERSEY, ASSIGNOR TO THE AMERICAN MULTIGRAPH COMPANY, OF CLEVELAND, OHIO, A CORPORATION OF OHIO.

TYPE-CASE.

1,089,151.

Specification of Letters Patent.

Patented Mar. 3, 1914.

Original application filed June 26, 1908, Serial No. 440,430. Divided and this application filed November 4, 1911. Serial No. 658,462.

To all whom it may concern:

Be it known that I, SAMUEL A. NEIDICH, of Edgewater Park, in the county of Burlington and State of New Jersey, have invented a certain new and useful Improvement in Type-Cases, whereof the following is a specification, reference being had to the accompanying drawings.

My application Serial No. 440,430, filed June 26, 1908, shows a type case which includes stationary typeholders or font channels. Associated with that type case is a movable typeholder comprising a rotary drum arranged to support a flexible type chase, forming the subject matter of Letters Patent of the United States #989,277, granted to me April 11, 1911, and including a plurality of type channels to which the type may be transferred from said font channels of the case, conveniently by means of a portable typeholder or composing stick such as described in Letters Patent of the United States #955,534, granted to me April 19th, 1910 and including a slotted metal tube having two tines at its end capable of embracing one of said abutments and engaging the bottom type in the channel above it. The present application which is a division of said prior application, relates to the typeholding drum and its coacting parts. Said drum comprises means for resiliently retaining the flexible chase wrapped upon it; said means being manually movable to release the chase and permit it to be removed from the drum for transference to a printing cylinder, or storage in plane position, and, said drum is provided with means whereby it may be completely rotated, or turned to successively present the type channels thereon in position to receive the type, including means whereby said drum may be detained in selected circumferential position.

My invention comprises the various novel features of construction and arrangement hereinafter described.

In the drawings, Figure I is a fragmentary plan view of a case conveniently embodying my invention. Fig. II is a vertical sectional view of said case, taken on the line II in Fig. I. Fig. III is a fragmentary sec-

tional view, taken on the line III in Fig. V. Fig. IV is a perspective view of a single type conveniently shaped to fit in said type channels. Fig. V is a fragmentary front elevation of said case.

In said figures; the case frame comprises the left and right hand standards 1 and 2, which are connected in rigid relation by the front standard 3, the rear standard 4 and the top rest plate 5. The type font channel 6 bars or rails 7, 8 and 9 are disposed in parallel relation in respective panels, being cross connected in rigid relation by their respective bearing plates 11, 12 and 13 and abutment plates 15, 16 and 17. Said channel 6 bars 7, 8 and 9 are so disposed as to receive in the spaces or channels 35, between them, type 36, which are conveniently shaped as shown in Fig. IV, having recesses 37 in their opposite sides to engage the flanges 38 of said channel bars and thus prevent accidental dislodgment of said type from said spaces 35. The abutment plates 15, etc., are provided with respective abutments 39, in alignment with respective type channels 35, 75 so as to support said type 36 and prevent their discharge in the direction of the length of the channels. However, discharge recesses 40 are provided between said abutments and the ends of the channel bars, of 80 such dimensions as to permit the type to be withdrawn singly when in contact with the abutments and such withdrawal may be effected by any suitable implement, for instance, the portable type holder or composing stick shown in my Patent No. 955,534. Such stick has two tines at its end capable of embracing one of said abutments 39 and projecting into the recesses 37, of the bottom type in the channel lying on said abutment, 85 so that said type may be withdrawn through the recesses 40.

The construction so far described, relates to the stationary part of the device, which is shown, described and claimed in my parent application referred to.

Said standards 3 and 4 have respective bearings 45 and 46 for the shaft 47 of the drum which has the opposite disk-like heads 49 and 50. The oscillatory hook frame 51 inc

is mounted to turn loosely on said shaft 47 and has at its opposite ends the arms 52 having the hook fingers 53 extending radially through the circumferentially extending slots 55 in said heads 49 and 50. The spring 58 which encircles said shaft 47 within said hook frame 51 is attached at its respectively opposite ends to said frame and the drum head 49, and the tension of said 10 spring is such as to press said movable hook fingers 53, in the direction of the arrow marked on Fig. II, toward the hook studs 60, which are rigidly secured in said heads 49 and 50. Said drum supports a flexible 15 type chase having the opposite end plates 61 and 62 with openings 63 and 64 respectively adapted for engagement with said hook studs 60 and hook fingers 53. Said chase plates 61 and 62 being curved to fit 20 the drum as shown in Fig. II, are connected by the rivets 66 in rectangular relation with the flexible spring metal bands 67, as shown in Fig. I, and, the series of type channel bars or rails 68 are disposed in parallel relation, transversely with respect to said bands 67 and each separately secured to the latter, conveniently by the rivets 69. Said channels 68 are tapered at their ends shown 25 at the right side of Fig. I, to afford at that edge of the chase, flaring entrances to the type spaces 71 between said channels, so that the type 36 may be readily slid into said spaces 71, from the composing stick aforesaid, with which they have been picked from 30 the case, as above described.

By turning the knob handle 73, which is frictionally engaged by the spring brake 72, interposed between said knob and the bearing 45 as shown in Fig. I, said drum 40 may be completely rotated to wrap the blanket about it, when such blanket is being put in place. The handle also provides means for turning the drum as desired to 45 present any selected type channel 71 in position to receive type from said composing stick. To hold the drum in such selected position I provide the drum head 50 with the circular rack 78 having recesses spatially corresponding with the type channels 71 in 50 said chase, as shown in Fig. I, and mount in the frame plate 3, below said knob 75, the detent plunger 80, which, as shown in Fig. III, is normally pressed inward by the spring 81 to enter said recesses between the 55 teeth of said rack 78. Said plunger 80 has the knob handle 82 provided with the stud 83, normally fitted in the socket 84 in said frame 3, as shown in Fig. III, so that said plunger 80 may reciprocate to successively 60 engage the teeth of said rack 78, when the drum is turned, without releasing said stud 83 from its socket. However, when it is desired to turn said drum freely; said plunger 80 which is also movable about its axis by

said knob 82, may be rendered inoperative 65 by withdrawing it until said stud 83 is freed from its socket, and then turning the knob 82 until said stud is presented against the plane face of said standard 3. There being no other means limiting the rotary movement of said drum; it may be observed that the construction and arrangement of said plunger 80 and rack 78, shown in Figs. I and III, is such that said plunger brings 70 said drum into the precise position desired 75 when the handle has brought it into substantially the desired position, and there detains it, by centering itself between the circumferentially opposed inclines of the selected recess in the rack. That is to say, as 80 said plunger enters each recess, between the rack teeth, it slightly rotates said drum, by bearing upon either of the oppositely inclined tooth faces until it is centered between them, and then prevents accidental 85 displacement of said drum from such selected position.

The devices above described may be cooperatively employed as follows: Type 36 are stored in the font spaces 35 in the case, 90 in accordance with the characters which they bear, as indicated by the index plates 85; said type resting upon the abutments 39. The composition is then made with the type 95 picked from their respective spaces by the composing stick aforesaid; the lines of type being successively transferred from said stick to the spaces 71, in the flexible chase carried by the drum; and the latter being turned to successively present said spaces for 100 loading. When the desired number of lines 105 of type have been inserted in the chase, the latter may be removed from the drum by turning the hook frame 51 in the drum, in the direction opposite to the arrow shown in Fig. II, by the handle 86, so that said chase plates may be lifted from their hooks and the chase unwrapped from the drum to be 110 stored in plane position or wrapped upon a printing drum.

When it is desired to redistribute in the case, type which have been used in said chase, the latter is returned to its position on the drum, as shown in Fig. I, and, the lines of type in the chase are successively 115 slid into the composing stick and from the latter are dropped one by one into their respective spaces 35 between the channel-bars 7, 8 and 9.

I do not desire to limit myself to the precise details of construction and arrangement above described as it is obvious that various modifications may be made therein without departing from the essential features of my invention as defined in the appended claims. 120 125

I claim:

1. The combination with a frame having shaft bearings; of a shaft mounted to rotate

in said bearings; a handle on one end of said shaft; a friction brake comprising a spring interposed between said handle and the adjacent bearing; a rotary drum having opposite end heads on said shaft between said bearings, and channels for carrying on its surface parallel lines of individual type; a circular rack on one of said heads, having recesses spatially corresponding with 10 said channels; means arranged to detachably engage said rack, in said recesses, including a plunger mounted to reciprocate in said frame, a spring normally pressing said plunger into engagement with said 15 rack, a handle on said plunger, whereby it may be withdrawn, and, a stud on said plunger normally fitted in a socket in said frame, but adapted to hold said plunger out of engagement with respect to said rack 20 when said plunger is withdrawn and turned with said stud away from its socket.

2. The combination with a frame having shaft bearings; of a shaft mounted to rotate in said bearings; a handle on one end of 25 said shaft; a friction brake for said shaft; a rotary drum having opposite end heads on said shaft between said bearings, and channels for carrying on its surface parallel lines of individual type; a circular rack on one of 30 said heads, having recesses spatially corresponding with said channels; means arranged to detachably engage said rack, in said recesses, including a plunger mounted to reciprocate in said frame, a spring normally 35 pressing said plunger into engagement with said rack, a handle on said plunger, whereby it may be withdrawn, and, means adapted to hold said plunger out of engagement with respect to said rack when 40 said plunger is withdrawn.

3. The combination with a frame; of a rotary drum, having channels for carrying on its surface parallel lines of type; a circular rack on one end of said drum, having 45 outwardly flared radial recesses spatially corresponding with said channels; means arranged to detachably engage said rack, in said recesses, including a plunger mounted to reciprocate in said frame, parallel with 50 the axis of the drum, a spring normally pressing said plunger into engagement with said rack, a handle on said plunger, whereby it may be withdrawn, and, means adapted to hold said plunger in inoperative position 55 when it is withdrawn.

4. The combination, with a rotatable shaft, of a pair of heads thereon having smooth peripheries, a rack carried on the side of one of said heads, a detent device cooperating 60 with said rack, a removable blanket composed of parallel rails adapted to be mounted on said heads, and a locking device for said blanket carried partly within the drum provided by said heads and shaft.

5. The combination with a frame; of a rotary drum journaled in said frame; means on said drum arranged to engage a flexible chase, including a pair of stationary hooks and a pair of oscillatory hooks projecting beyond the circumference of said drum; a 70 shaft journaled in said drum and carrying said oscillatory hooks; a spring tending to rock said shaft, and press said hooks in one direction; and an operating arm on said hook shaft. 75

6. The combination of a drum comprising a central shaft and heads mounted thereon, a type chase adapted to seat on the drum and having openings near its ends, a stationary hook carried by the drum and adapted to 80 occupy one of the openings in the chase for holding one end of the chase, a movable hook mounted on said shaft for holding the other end of the chase, and means for moving said hook to engage or release the chase. 85

7. The combination of a rotary shaft, a pair of disk-like heads thereon, a flexible type chase adapted to be mounted on said heads, a hook device movably mounted on said shaft for locking the chase on the heads, 90 means for turning said shaft to bring different parts of the flexible chase into loading position, and means for locking the chase and its holder in desired position.

8. The combination of a rotary shaft, a 95 pair of disks rigidly mounted thereon and having peripheral flanges to provide a cylindrical seat for a flexible chase, a sleeve on said shaft between the disks, a pair of arms projecting from said sleeve through 100 openings in said flanges, hooks on said arms adapted to engage the chase, and a spring to hold said hooks in engaging position.

9. The combination, with a frame, of a rotary shaft mounted therein, means for 105 turning the shaft, a pair of disks on the shaft, stationary hooks projecting from the respective disks, a sleeve loose on the shaft between the disks, a pair of arms extending from said sleeve having hooked ends adjacent to the disks, a flexible blanket adapted to be held on the disks by the stationary and movable hooks, a spring tending to turn said sleeve, and an operating arm projecting from the sleeve and accessible in the space 110 between the ends of the flexible blanket held by the hooks. 115

10. The combination of a movable type-holder including parallel channels mounted upon a rotary drum, means carried by said 120 drum detachably connecting said channels with the drum, including stationary hook studs, movable hook fingers, a lever operatively connected with said hook fingers, and means for locking said drum with any desired channel in receiving position. 125

11. The combination, with a frame, of a rotatable shaft journaled therein, heads on

the shaft, a removable blanket comprising parallel rails held equi-distant, means for holding such blanket on the heads including movable hook fingers, means to hold said fingers in active position engaging the blanket, means to move said fingers to inactive position, and means for holding the structure described in various adjusted positions.

In testimony whereof, I have hereunto signed my name at Burlington, New Jersey, this first day of November, 1911.

SAMUEL A. NEIDICH.
